UNITED STATES PATENT OFFICE.

GEORGE A. ROBBINS, OF SLATE HILL, NEW YORK, ASSIGNOR OF ONE-THIRD
TO SAMUEL W. HORNBECK, OF SAME PLACE.

DESIGN FOR A POT-SCRAPER.

SPECIFICATION forming part of Design No. 32,537, dated April 17, 1906.

Application filed March 24, 1906. Serial No. 10,097. Term of patent 14 years.

To all whom it may concern:

Be it known that I, GEORGE A. ROBBINS, a citizen of the United States of America, and a resident of Slate Hill, in the county of Orange and State of New York, have invented a certain new and original Design for a Pot-Scraper, for which the following is a specification.

Figure 1 is a perspective view of a pot-scraper embodying my invention. Fig. 2 is a plan view of the same upon an enlarged scale.

The four blades a a' a^2 a^3 of the scraper are serrated along their lower edges and are at substantially the same angle to the line of handle a^4 .

The blades, with the exception of the curved blade a , are straight. Blades a' and a^3 each meets blade a at an acute angle and blade a^2 at an obtuse angle.

Blade a is connected to the handle a^4 by two wires a^5 and a^6 and blade a^2 by a wire a^7 . The wires are plaited at their outer ends, and the plaited portion enters handle a^4 .

What I claim is—

The design for a pot-scraper substantially as shown and described.

GEORGE A. ROBBINS.
